Patented Sept. 5, 1922.

Inventor,
Ira A. Burnett.
By Chas. D. Illman
Attorney.

UNITED STATES PATENT OFFICE.

IRA A. BURNETT, OF CHICAGO, ILLINOIS.

DESIGN FOR A COMBINED BULLETIN AND TIME BOARD.

Application filed December 23, 1921. Serial No. 524,505. Term of patent 7 years.

To all whom it may concern:

Be it known that I, IRA A. BURNETT, a citizen of the United States, residing at Chicago, in the county of Cook and State of Illinois, have invented a new, original, and ornamental Design for a Combined Bulletin and Time Board, of which the following is a specification, reference being had to the accompanying drawing, forming part thereof.

The figure is a perspective view of a combined bulletin and time board, showing my new design.

I claim:—

The ornamental design for a combined bulletin and time board, as shown.

IRA A. BURNETT.
